Patented Sept. 27, 1927.

UNITED STATES PATENT OFFICE.

EDWARD WILSON, OF ST. LOUIS, MISSOURI, ASSIGNOR TO THE NATIONAL PUMP & COMPRESSOR COMPANY, OF ST. LOUIS, MISSOURI, A CORPORATION OF DELAWARE.

COMPRESSOR.

Application filed November 17, 1923. Serial No. 675,384.

This invention relates to compressors.

An object of the invention is to provide a compressor designed and adapted particularly for use as a household refrigerator unit, but also capable of use for commercial purposes such as in meat markets, grocery stores, and other places.

Another object of the invention is to provide an improved compressor overcoming and eliminating defects and objections in the case of certain machines now in use by increasing the volume of gas displaced by the piston, in comparison with the theoretical displacement, by eliminating cylinder 10 and valve chamber clearances, to overcome and prevent noisy operation; to provide efficient means for preventing loss of refrigerant from the compressor to the atmosphere, which usually occurs through the stuffing 15 box and which requires frequent adjustment and replacement of packing; to prevent the superheating of the cylinder which results in a low volume of gas displaced by the piston; and to prevent escape of oil with the 20 compressed gas into the expansion coils.

Another object is to provide a compressor of simple and improved construction; other objects and advantages will appear from the following description, reference being made 25 to the drawing in which

Fig. 1 is a vertical longitudinal sectional view of the compressor.

Fig. 2 is a vertical cross sectional view.

In the embodiment of the invention shown 30 in the drawing the piston 1 is of the trunk type and is equipped with a hydraulic leather packing 2 held in place by a ring 3 pressing the packing close against the inner periphery of the cylinder wall. The ring is held 35 in place by a clamping element 4 secured on a projection 5 from the end wall of the piston. The connecting rod 6 from the piston 1 to the crank shaft 8 operates the piston when the crank shaft is rotated. The crank shaft 40 is above the piston which, as shown, is single acting although the invention is not restricted to a compressor embodying a single acting piston. The crank shaft 8 has a worm wheel 45 attached thereto and is driven by a worm 9 attached thereto and is driven by a worm 50 10 on a motor driven shaft 11.

The piston operates within a cylinder 12 and the other working parts described are enclosed within a casing 13 designed and adapted to contain a sufficient quantity of 55 lubricant to keep the working parts well lu-

briated. The lower portion of the wheel 9 operates within a deepened part 14 of the casing 13 which contains oil that will be taken up by the wheel to lubricate other parts.

The device comprises a vertical compression chamber 15 the upper end of which is conical. The conical shape of the upper end of the compression chamber prevents noise that would result from impact of the liquid 60 against a flat wall. An inlet passage to the upper end of the compression chamber is provided, the same comprising a chamber 16 opening at its upper side into the conical upper end of the chamber 15 through a passage 65 17. The suction inlet 18 is controlled by a valve 19 held to its seat by a spring 20. The discharge passage 21 from the upper end of the chamber 15 opens into a small chamber 22 which opens into the discharge 70 outlet 23. The passage 21 is controlled by a valve 24 actuated to its seat by a spring 25. A relatively small venting passage 26 forms 75 communication from the chamber 22 into the upper end of the chamber 15.

Below the piston 1 is a relatively large chamber 27 which with the chamber 15 forms a modified type of U-tube. The chamber 27 is of considerably larger cross sectional area 80 than the chamber 15.

The U-tube comprising the chambers 15 and 27 contains a quantity of mercury indicated by the heavy shading on the drawing. Floating on the top of the mercury in the chamber 27 is a quantity of heavy oil which 85 together with the amount of mercury in the lower portion of the chamber 27 completely fills said chamber 27 to the exclusion of all gas or air. The heavy oil in the chamber 27 is indicated by the light shading. It will be 90 noted that a small quantity of mercury is in the discharge valve chamber 22 and that the suction valve chamber 16 will always retain mercury up to the bottom of the opening 17. A small quantity of mercury will remain in 95 the discharge valve chamber when the device is in operation and at each operation of the piston 1 a small quantity of mercury will pass the valve 24. To return the mercury to the chamber 15 the venting passage 26 is 100 provided.

When the piston 1 is raised during operation of the compressor the column of mercury in the chamber 15 will fall and the 105 gas will pass through the suction inlet into 110

the upper end of the chamber 15. Downward movement of the piston 1 causes an upward movement of the column of mercury in the chamber 15 with consequent compression and discharge of the gas.

The piston 1 being single acting it will be seen that when working with a refrigerant gas the range of pressure of which is above atmosphere there will always be an upward thrust against the piston and bearings and an absence of any knock, due to reciprocation of the load upon the bearings. This feature in connection with the slow speed and large bearing surfaces produces silent operation.

The oil in the crank case is under atmospheric pressure which makes it unnecessary to provide a stuffing box to prevent escape of the refrigerant from the compressor where the drive shaft enters the case, as is common with the usual type of machine. The leather packed piston sealed by heavy oil above the mercury in the chamber 27 prevents escape of the refrigerant.

The chamber 15 is partly enclosed by a water jacket 28 which, because of the slow movement of the piston, prevents superheating.

It will be noted that the oil never enters the chamber 15 and that the communication 29 from the chamber 27 to said chamber 15 is always filled with mercury and that the mercury fills the bottom of the chamber 27. This provides a complete separation of the refrigerant and the lubricating oil which is a highly desired feature of the invention.

A removable screw 30 and enclosing cap 31 afford access to the chamber 27 in order to correct any variation in the relative amounts of oil and mercury.

From the foregoing it will be seen that my invention comprises a novel structure and improved mechanism producing a silent and continuously lubricated compressor in which the refrigerant gas is prevented from entering the oil in the chamber 27 by the column of mercury in the chamber 15 and in the lower portion of said chamber 27. Superheating is prevented by the efficient lubrication and by the water jacket 28.

I contemplate such variations within the scope of the appended claims as may be found desirable to obtain the intended objects and purposes of the invention.

I do not restrict myself unessentially, but what I claim and desire to secure by Letters Patent is:—

1. A compressor comprising a compression chamber having the interior of its upper end tapered and having a gas inlet through the wall of said tapered portion and a gas outlet at the apex of said tapered portion, a chamber above said compression chamber having a gas outlet therefrom and a vent passage opening into the compres-

sion chamber, a valve in said second chamber controlling the outlet passage from said compression chamber, means for maintaining a liquid seal for said inlet passage, a cylinder, a chamber of larger area than said cylinder into which said cylinder opens and having a passage opening into the compression chamber entirely below the lower end of the cylinder, and a piston operating in said cylinder.

2. A compressor comprising a compression chamber having an inlet passage and an outlet passage, an additional chamber having an opening into the lower end of said compression chamber and having its upper wall relatively a considerable distance above said opening, a cylinder opening through the upper wall of said additional chamber and having its lower end between said opening and the upper wall of said additional chamber, and a piston operating in said cylinder and having a down stroke terminating above said opening from said additional chamber to said compression chamber.

3. A compressor comprising a compression chamber having an inlet passage and an outlet passage, an additional chamber having an opening into the lower end of said compression chamber and having its upper wall relatively a considerable distance above said opening, a cylinder opening through the upper wall of said additional chamber and having its lower end between said opening and the upper wall of said additional chamber, a piston operating in said cylinder and having a down stroke terminating above said opening from said additional chamber to said compression chamber, a quantity of mercury in said chambers sufficient to fill the compression chamber and the passage therefrom to said additional chamber when said piston is down, and a quantity of oil in said additional chamber supported by the mercury and completely filling the remainder of said additional chamber when said piston is down.

4. A compressor comprising a compression chamber having the interior of its upper end tapered and having a gas inlet through the wall of said tapered portion and a gas outlet at the apex of said tapered portion, a chamber above said compression chamber having a gas outlet therefrom and a vent passage opening into the compression chamber, a valve in said second chamber controlling the outlet passage from said compression chamber, means for maintaining a liquid seal for said inlet passage, a cylinder, a chamber of larger area than said cylinder into which said cylinder opens and having a passage opening into the compression chamber entirely below the lower end of the cylinder, a piston operating in said cylinder, and mechanism for operating said piston on up and down strokes in which

the down strokes terminate above the opening from said last named chamber to said compression chamber.

5. A compressor, comprising a chamber having the interior of one end thereof tapered, an outlet for compressed gas opening from the apex of the tapered end of the chamber, a valve chamber into which said outlet opens, a valve in said valve chamber controlling said outlet, a passage from said valve chamber independent of the outlet opening into the first-named chamber, a gas inlet opening into the first-named chamber near said outlet, an additional chamber communicating with the first-named chamber, a quantity of mercury confined in said chambers sufficient to fill the first-named chamber entirely and also fill the lower portion of the second chamber to a height sufficient to fill the communication between said chambers, a quantity of oil in said additional chamber, and a piston operating against the oil to move the mercury to effect compression.

25. 6. A compressor comprising a compression chamber having the interior of its upper end tapered and having a gas inlet and a gas outlet, a cylinder, a chamber of larger area than said cylinder into which said cylinder opens and having a passage opening into the compression chamber entirely below the lower end of the cylinder, a piston operating in said cylinder, and means for maintaining a liquid seal in said inlet passage.

35. 7. A compressor, comprising a chamber having the interior of one end thereof tapered, a gas inlet opening into the tapered end of the chamber, an outlet for the compressed gas from the apex of the tapered end of the chamber, a quantity of liquid in said chamber that will not absorb gas, a quantity of oil in the end of the chamber opposite from said outlet, means for correcting variations in the amounts of oil and liquid, mechanism acting upon the oil to move said liquid to effect compression, and means for preventing oil from passing into

that part of the chamber in which compression is effected.

8. A compressor, comprising a chamber having the interior of one end thereof tapered, a gas inlet opening into the chamber, an outlet for the compressed gas from the tapered end of the chamber, a quantity of liquid in said chamber that will not absorb gas, a quantity of oil in the end of the chamber opposite from said outlet, mechanism acting upon the oil to move said liquid to effect compression, and a device for correcting any variation in the relative amounts of oil and liquid.

9. A compressor, comprising a U-tube, one leg of which is tapered on the inside of its upper end and the other leg of which is of greater cross sectional area than the first-named leg, a piston operating toward and away from said tube of larger cross sectional area, a quantity of mercury in the first leg of the tube and in the bottom of the second leg of the tube sufficient in one position of the piston to fill the first leg of the tube and to close communication between said legs, and a quantity of oil in the second leg of the tube filling the space between the mercury and the piston.

75. 10. A compressor, comprising a U-tube, one leg of which is tapered on the inside of its upper end and the other leg of which is of greater cross sectional area than the first-named leg, a piston operating toward and away from said tube of larger cross sectional area, a quantity of mercury in the first leg of the tube and in the bottom of the second leg of the tube sufficient in one position of the piston to fill the first leg of the tube and to close communication between said legs, a quantity of oil in the second leg of the tube filling the space between the mercury and the piston, an inlet to the leg of the tube containing the tapered end, 90 a discharge outlet from said leg of the tube, and valves controlling said inlet and outlet respectively.

EDWARD WILSON.
